UNITED STATES PATENT OFFICE.

WILLIAM JARRELL, OF LAVACA, ARKANSAS, ASSIGNOR OF ONE-HALF TO
ROBERT A. ROWE AND STYLUS T. ROWE, OF GREENWOOD, ARKANSAS.

NUT-LOCK.

SPECIFICATION forming part of Letters Patent No. 665,011, dated January 1, 1901.

Application filed May 22, 1900. Serial No. 17,600. (No model.)

To all whom it may concern:

Be it known that I, WILLIAM JARRELL, a resident of Lavaca, in the county of Sebastian and State of Arkansas, have invented certain new and useful Improvements in Nut-Locks; and I do hereby declare the following to be a full, clear, and exact description of the invention, such as will enable others skilled in the art to which it appertains to make and use the same.

My invention relates to an improvement in nut-locks, the object of the invention being to provide an improved device of the above-mentioned character which can be readily placed in position and which will effectually lock the nut against accidental turning, but which will by the aid of proper tools permit the removal of the nut when desired.

With this object in view the invention consists in certain novel features of construction and combinations and arrangements of parts, as will be more fully hereinafter described, and pointed out in the claim.

In the accompanying drawings, Figures 1 and 2 are views illustrating my improvements, and Fig. 3 is a view of the lock.

A represents an ordinary rail, and B fish-plates disposed on each side thereof between the head and flanges, and said fish-plates are provided at their lower edges with flanges 1, which extend out over the flanges of the rail. The fish-plates B and web of the rail A are provided with aligned holes for the passage of a bolt C, screw-threaded at its end for the reception of the nut D.

My improved nut-lock E is disposed between the fish-plate B and nut D and comprises a metal plate 2, preferably rectangular in shape and adapted to rest on the flange 1 on the fish-plate and provided near its right side with a hole for the passage of the bolt C. The plate 2 is provided at its upper end on its right side with a horizontal arm 3, inclined or beveled on its outer face, and to which beveled face is secured a spring 4, preferably

of steel, by means of rivets 5, passing through said arm 3 and spring 4, and it will be seen that owing to the beveled face of arm 3 the lower end of spring 4 will project out beyond the outer face of plate 2, so as to lie in the path of the nut and prevent its accidental turning; but when the nut is screwed home its corners will slide over the spring and depress the same until free thereof, when the spring will spring outward, so that its edge will lie in the path of the side of the nut and prevent the unscrewing of the latter. However, when it is desired to remove the nut it is simply necessary to force the lower end of spring 4 inward by means of the proper tool, when the nut can be readily removed.

My improved lock may also be put to various other uses besides on rails, and various slight changes might be resorted to in the general form and arrangement of the several parts described without departing from the spirit and scope of my invention, and hence I would have it understood that I do not limit myself to the precise details set forth, but consider myself at liberty to make such slight changes and alterations as fairly fall within the spirit and scope of my invention.

Having fully described my invention, what I claim as new, and desire to secure by Letters Patent, is—

A nut-lock comprising a plate having a hole therein, an arm projecting laterally from said plate, said arm beveled on its outer face and forming an inclined seat disposed at an angle to the face of the plate, and a flat spring-plate fixed at one end to said inclined seat and projecting outwardly beyond the plane of the face of the first-mentioned plate.

In testimony whereof I have signed this specification in the presence of two subscribing witnesses.

WILLIAM JARRELL.
